COIN SORTER

Leonard T. Miconi, Reading, Pa.

Application April 4, 1947, Serial No. 739,427

5 Claims. (Cl. 133—3)

1

The present invention relates to a coin sorting device.

The primary object of the present invention is to provide a simple and efficient apparatus for sorting coins of various denominations, which is operated by gravity to eliminate all moving parts.

The main object of the present invention is to provide a coin sorting apparatus adapted to sort a large number of coins of different denominations at one time.

Another object is to provide a coin sorting device which comprises a multiple coin trackway, with each trackway having coin rejecting means to insure against coins of one denomination mixing with coins of another denomination.

It is the broad concept of the present invention to provide a coin sorting apparatus comprising a coin slide in the coin pathway with a V-shaped coin trackway, with said coin trackway having slots of progressively increasing dimensions adapted to receive coins of various denominations.

Other and further objects and advantages of the present invention will be apparent from the following description thereof and from the claims appended hereto.

Referring now to the drawing wherein like numerals refer to like or corresponding parts throughout the several views,

Figure 1 is a top plan view of the coin sorting apparatus, and embodying the features of the present invention.

Figure 2 is a side elevation, in section, of the coin sorting device.

Figure 3 is a sectional view taken along the line 3—3 of Figure 1 in the direction of the arrows,

Figure 4 is a sectional view taken along the line 4—4 of Figure 1 in the direction of the arrows,

Figure 5 is a sectional view taken along the line 5—5 of Figure 1 in the direction of the arrows, and

Figure 6 is a sectional view taken along the line 6—6 of Figure 2 in the direction of the arrows.

Referring to the drawing, the numeral 10 generally represents the coin sorting device comprising a metallic frame, which is preferably rectangular in shape, and may be constructed of any desired material, such as metal or plastic.

The coin sorting device includes a coin slide apparatus generally indicated by the numeral 11 and comprising a coin slide 12 fastened within an arcuate member 13 which is provide at the lower portion thereof with a raised W-shaped portion 14. The coin slide assembly 11 is se-

2

cured to a coin trackway assembly comprising two V-shaped coin trackways 16 and 17, by means of a removable screw 18 and a nut 19.

It is to be understood that one, two or any number of V-shaped coin trackways with an appropriate coin slide assembly may be employed. It is also to be understood that the coin slide assembly 11 may be constructed integral with the coin trackway assembly wherein the side walls of the coin slide or coin feeder assembly merge with the outer side walls of the V-shaped trackway or trackways.

The coin slide 12 is positioned at an angle from the horizontal so that coins disposed thereon will slide downwardly under the influence of gravity, against the arcuate member 13, which is likewise disposed at an angle from the horizontal, to propel coins downwardly therefrom. As the coins leave the coin slide 12 they contact the inner wall of the arcuate member 13 and slide downwardly into either one side or the other of the W-shaped coin portion 14, to continue into the V-shaped coin trackway 16 or into the V-shaped coin trackway 17.

The V-shaped coin trackway 16 is provided with a pair of oppositely disposed coin rejection slots 20 and 21 on opposite sides of the coin pathway 16a, with the result that only one coin can pass the area of the coin rejection slots 20 and 21 at any one time. It is to be noted that the diameter of the coin pathway 16a is such, at the area of the coin rejection slots 20 and 21, that no two coins, one superimposed on the other, can roll by said coin rejection slots. Consequently, the coin rejection slots 20 and 21 provide a simple means of keeping the coins separated as they roll down the trackway 16. The apex of each V-shaped coin trackway 16 and 17 respectively, is so constructed that coins rolling onto the coin pathways 16a and 17a fall either to one side or the other against a side wall of the V-shaped trackway.

As the coins roll into the coin trackway 16, they fall either to one side or the other of the V-shaped trackway and continue their downward path under the influence of gravity. As the coin passes the coin rejection slots 20 and 21, it will continue its downward path until it falls into an appropriate slot.

The coin trackway 16 is provided with a plurality of pairs of spaced-apart oppositely disposed rectangular apertures of progressively increasing dimensions and indicated by the numerals 22, 23, 24 and 25 respectively. In addition,

there is a coin slot 26 at the end of the coin pathway 16a.

As pointed out, the coin slots 22, 23, 24 and 25 are preferably of rectangular shape and of increasingly larger dimensions. Coin slots 22 have dimensions such that a ten cent piece will fall therethrough, while the larger coins will continue downwardly on the coin pathway 16a. Coin slots 23 have a dimension to accommodate a one cent piece, while slots 24 and 25 are adapted to receive five cent pieces and quarters respectively which roll down the coin pathway 16a. The slot 26 disposed at the lower end portion of the coin pathway 16a is adapted to receive fifty cent pieces.

The coin trackway 17 is similar in construction to the coin trackway 16 and is provided with a coin pathway 17a, rejection slots 27 and 28, and a plurality of pairs of oppositely disposed spaced-apart coin slots 29, 30, 31 and 32, with a fifty cent coin slot 33 at the bottom of the coin pathway 17a.

The coin sorting device 10 is provided with a utility cabinet 34 which swings on hinges 35, and may be locked into place by rotatable lug 36. There is provided a handle 37 secured to the door of the cabinet 34.

A slideable drawer 38 is secured beneath the coin rejection slots 20 and 21 and 27 and 28, to receive any coins that fall through these coin rejection slots. As the drawer 38 fills with rejected coins, it can be withdrawn and the coin content thereof can be again disposed on the coin slideway 12.

Beneath each of the pairs of coin apertures 22—29, 23—30, 24—31 and 25—32, there is disposed a drawer indicated respectively by the numerals 39, 40, 41 and 42, with each of the said drawers provided with an appropriate handle. Likewise, a drawer 43 is secured beneath the coin slots 26—33.

A handle 44 is secured to the front end of the coin sorting apparatus while a handle 45 is secured to the rear wall thereof, so that the coin sorting apparatus may be easily lifted and carried from place to place.

In operation, coins of various denominations are disposed on the coin slide 12 and slide downwardly therefrom under the influence of gravity. The coins hit the arcuate member 13 where they reverse their direction of travel and are propelled downwardly under the influence of gravity into either the V-shaped coin trackway 16 or the V-shaped coin trackway 17. It should be noted that with a plurality of V-shaped coin trackways that a greater number of coins of various denominations can be handled at one time.

As the coins roll into the V-shaped coin trackways 16 and 17, they hug either one side wall or the other of said coin trackways. Should one coin be superimposed on the other as they roll downwardly along the coin trackways, the superimposed coin will fall into one of the coin rejection slots, as the coin pathway at the area of the coin rejection slots is of such a diameter that only one coin can pass at one time. The superimposed coin must fall into one or the other of the coin rejection slots.

After passing the area of the coin rejection slots, the coins will fall into the appropriate coin slot depending upon the particular denomination of the coin.

Various modifications of the present invention will be apparent to those skilled in the art without departing from the scope thereof and it is

therefore desired to be limited only to the claims appended hereto.

What I claim is:

1. A gravity operated coin sorting device comprising, a coin slide, a plurality of V-shaped coin trackways in the coin pathway leading from said coin slide, each of said V-shaped coin trackways being provided with a pair of oppositely disposed coin rejecting slots one slot in each side wall thereof, each of said slots being positioned at a distance slightly less than the thickness of the thinnest coin from the apex of the V-shaped coin trackway to prevent two rolling coins one resting against the other from together passing any one of said slots at the same time without one of said rolling coins falling through one of said rejecting slots, said coin rejecting slots being followed by a plurality of pairs of oppositely disposed spaced-apart apertures of progressively larger dimensions extending along each of said coin trackways to receive coins of different denominations rolling down said coin trackways, each of said coin trackways being provided with a slot at the bottom portion thereof to receive coins which pass the said spaced-apart apertures, and receptacles to receive the sorted coins.

2. A gravity operated coin sorting device comprising, a coin slide, a plurality of V-shaped coin trackways in the coin pathway leading from said coin slide, each of said V-shaped coin trackways being provided with a pair of oppositely disposed coin rejecting slots one slot in each side wall thereof, each of said slots being positioned at a distance slightly less than the thickness of the thinnest coin from the apex of the V-shaped coin trackway to prevent two rolling coins one resting against the other from together passing any one of said slots at the same time without one of said rolling coins falling through one of said rejecting slots, said rejecting slots being followed by a plurality of pairs of spaced-apart apertures of progressively larger dimensions extending along each of said coin trackways to receive coins of different denominations rolling down said coin trackways, and receptacles to receive the sorted coins.

3. A gravity operated coin sorting device comprising, a coin slide, a V-shaped coin trackway in the coin pathway leading from said coin slide, said V-shaped coin trackway being provided with a pair of oppositely disposed coin rejecting slots one slot in each side wall thereof, each of said slots being positioned at a distance slightly less than the thickness of the thinnest coin from the apex of the V-shaped coin trackway to prevent two rolling coins one resting against the other from together passing any one of said slots at the same time without one of said rolling coins falling through one of said rejecting slots, said coin rejecting slots being followed by a plurality of pairs of oppositely disposed spaced-apart apertures of progressively larger dimensions extending along said coin trackway to receive coins of different denominations rolling down said coin trackway, and a receptacle beneath each of said pairs of apertures to receive coins falling there-through.

4. A gravity operated coin sorting device comprising, a V-shaped coin trackway provided with a pair of oppositely disposed coin rejecting slots one slot in each side wall thereof, each of said slots being so positioned with respect to the apex of the V-shaped coin trackway as to prevent two rolling coins one resting against the other from together passing any one of said slots at the same

time without one of said rolling coins falling through one of said rejecting slots, and said rejecting slots being followed by a plurality of pairs of spaced-apart apertures of progressively larger dimensions extending along said coin trackway to receive coins of different denominations rolling down said coin trackway.

5. A gravity operated coin sorting device comprising, a coin slide, a V-shaped coin trackway in the coin pathway leading from said coin slide, 10 said V-shaped coin trackway being provided with a pair of oppositely disposed coin rejecting slots one slot in each side thereof, each of said slots being so positioned with respect to the apex of the V-shaped coin trackway as to prevent two 15 rolling coins one resting against the other from together passing any one of said slots at the same time without one of said rolling coins falling through one of said rejecting slots, said coin rejecting slots, being followed by a plurality of pairs 20 of spaced-apart oppositely disposed apertures of

progressively larger dimensions extending along said coin trackway to receive coins of different denominations rolling down said coin trackway, said V-shaped coin trackway being provided with 5 a slot at the bottom portion thereof to receive coins which have rolled past said spaced-apart apertures, and receptacles adapted to receive the sorted coins.
